(57) **CLAIM**

The ornamental design for component of electrical connector, as shown and described.

DESCRIPTION

FIG. 1 is a front view of a component of an electrical connector.

FIG. 2 is a rear view of the component of the electrical connector.

FIG. 3 is a left view of the component of the electrical connector.

FIG. 4 is a right view of the component of the electrical connector.

FIG. 5 is a top view of the component of the electrical connector.

FIG. 6 is a bottom view of the component of the electrical connector; and,

FIG. 7 is a perspective view of the component of the electrical connector.
